CLAIM

The ornamental design for a quick release tent mount as shown and described.

DESCRIPTION

FIG. 1 is a perspective view of a quick release tent mount showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a top perspective view of a quick release tent mount showing the new design in its environment of use.

The broken lines illustrate the environments in which the design is embodied and portions of the quick release tent mount that form no part of the claimed design.
